(57) **CLAIM**

The ornamental design for a semiconductor lighting unit, as shown and described.

DESCRIPTION

FIG. 1 is an isometric illustration of the semiconductor lighting unit.

FIG. 2 is a front view of the semiconductor lighting unit.

FIG. 3 is a rear view of the semiconductor lighting unit.

FIG. 4 is a right side view of the semiconductor lighting unit.

FIG. 5 is a left side view of the semiconductor lighting unit.

FIG. 6 is a top view of the semiconductor lighting unit; and,

FIG. 7 is a bottom view of the semiconductor lighting unit.

The broken line showing of the wire is included for the purpose of illustrating only and forms no part of the claimed design.
